UNITED STATES PATENT OFFICE

DONALD F. SPROUL, OF CHICAGO, ILLINOIS, ASSIGNOR TO CARDWELL WESTINGHOUSE COMPANY, A CORPORATION OF DELAWARE

DRAFT GEAR

Application filed November 2, 1929, Serial No. 404,221. Renewed October 29, 1931.

The invention relates to means for insuring the correct assembly of easily misplaced elements of a draft gear, especially applicable to gears of the well known Cardwell type although not necessarily limited thereto.

In the Cardwell gear there is employed, in connection with each of the followers, a pair of triangular wedge blocks which slidably engage the face of the follower and cooperate with other wedging elements of the gear, the triangular blocks being forced apart as the gear is compressed. It frequently happens that the assembly of the elements of a draft gear is done by mechanics who are not especially trained to this particular work, and where the triangular blocks have wedging faces of unequal length there is a strong probability that such a workman will position them improperly, in which event the gear would be rendered of little practical value.

It is the object of this invention to insure the proper assembly of the elements, and to render it impossible to improperly position the triangular blocks.

The invention consists in a chambered follower provided with guideways which cooperate with the triangular blocks to insure the correct positioning of the latter, and a preferred embodiment of the invention is herein disclosed.

In the accompanying drawings—

Fig. 1 is a detail plan section of a Cardwell gear embodying the invention;

Fig. 2 is a detail transverse section on the line 2—2 of Fig. 1;

Fig. 3 is a plan view, partly in section, of one of the followers;

Fig. 4 is a detail section corresponding with that of Fig. 2, showing a modification; and

Fig. 5 is a view similar to Fig. 3, showing a modified form of construction of the follower.

A pair of center or draft sills is shown at 10, and between them is enclosed a Cardwell gear comprising a pair of chambered followers 11, 12; a pair of triangular wedge-blocks 13, 14, and 15, 16, seated against the inner face of a transverse wall of each follower; a central wedging element 17 cooperating with

the inner wedging faces of each pair of the triangular blocks; a pair of outer wedge elements 18, 19, each cooperating with the outer faces of one of the triangular wedge-blocks of each pair; a straining rod 20 setting through the elements 17, 18 and 19, and through the sills 10; and helical springs 21, 22, encircling the outer end portions of the rod 20 and reacting upon the elements 18, 19, against spring seats 23, 24, fixed upon the ends of the rod.

In accordance with later practice the triangular blocks 13, 14, have wedging faces of unequal length, and consequently of different pitch, their inner or adjacent faces being the shorter. Unless provision is made for preventing improper assembly an inexperienced workman, failing to observe the comparatively slight difference between the two wedging faces, might easily set the blocks with their wrong faces adjacent.

For the purpose of rendering such mistakes impossible the followers are provided with guideways 25 in one or both of their horizontal faces, and the triangular blocks are provided with angular bosses 26 on one or both of their ends, for cooperating with these channels, the length of the boss being slightly less than the width of the channel. The channel is made T-shape, as shown in Fig. 3, the cross 27 of the T being adjacent the inner end of the channel and the stem thereof extending to the margin of the wall in which it is formed.

In the modification of Fig. 5, the channel 25 is shown as L shape, having but a single lateral extension 28 at its inner end, and a similar channel, as indicated in dotted lines at 29, is formed in the other horizontal wall of the follower.

In assembling the parts one of the blocks, as 14, is first introduced into the chamber of the follower 11, its boss 26 sliding freely within the longitudinal portion or stem of the channel 25, and when the block reaches the transverse wall of the follower it is moved to the right or to the left, as may be necessary to position it with its longer wedging face outward.

The block 13 being now similarly intro-

duced, the left rearward corner of its boss 26 will pass the angle at the left of the channel as the block comes into contact with the inner wedging face of the block 14, whereupon the block 13 may be moved to the left to operative position.

It will be seen that if an error has been made in inserting the block 14, so that its more obtuse wedging face is to the left, this face will so far trespass upon the stem portion of the channel, projected, that it will obstruct the entrance of the block 13 and compel the shifting of the block 14 to the left instead of to the right before the completion 10 of the assembly can be accomplished. Should the workman attempt to introduce either of the blocks with the wrong face in advance, its entrance will be similarly prevented; it being necessary only that, as shown, the distance from either of the wedge faces of the block to the most remote part of the boss be greater than the width of the channel extension.

Obviously the guide channel may have either the T form of Fig. 3 or the L form of Fig. 5. When the T form is followed there may be a channel in both the upper or lower walls of the follower, or in one only, and in the latter case each of the blocks will be provided with a boss at one end only. Where the L form is employed there will be a channel in both the top and bottom walls, and each of the blocks will be provided with a boss at but one end, as shown in Fig. 4.

The guideway may, if desired, be in other than channel form, and the construction may be variously modified from that disclosed without departing from the scope of the invention, which, in its broader aspects, includes any arrangement which will prevent the improper positioning of wedge-blocks of the character described.

I claim as my invention—

1. A draft gear comprising, in combination, a chambered follower, a pair of triangular wedge-blocks slidably engaging the vertical face of the follower, the exposed sides of the blocks being of unequal length, the follower having one of its horizontal walls provided with a central guide channel extending inwardly from its margin and laterally at its inner end, and each of the blocks having an angular boss on one end for engaging the channel.

2. A draft gear comprising, in combination, a chambered follower, a pair of triangular wedge-blocks slidably engaging the vertical face of the follower, the exposed sides of the blocks being of unequal length, the follower having each of its horizontal walls provided with a central guide channel extending inwardly from its margin and laterally at its inner end, and each of the blocks having an angular boss on one end for engaging the channel.

3. A draft gear comprising, in combination, a chambered follower, a pair of triangular wedge-blocks slidably engaging the transverse vertical face of the follower, their exposed faces being of unequal length, each block having an angular boss on one end and the follower having a central T-shaped guide channel in one of its horizontal walls, the stem of the T extending inwardly from the margin of the wall.

4. A draft gear comprising, in combination, a chambered follower, a pair of triangular wedge-blocks slidably engaging the transverse vertical face of the follower, their exposed faces being of unequal length, the blocks having angular bosses on their ends and the follower having central T-shaped guide channels in its horizontal walls, the stem of the T extending inwardly from the margin of the wall and its cross member being adjacent the vertical wall of the follower.

5. A draft gear comprising, in combination, a chambered follower having T-shaped guide channels in its horizontal walls, the stem of the T extending inwardly from the margin of the wall, and a pair of wedge-blocks having the form of scalene triangles in sliding engagement with the transverse wall of the follower, the blocks having an angular boss on each end for cooperating with the channels.

6. A draft gear comprising, in combination, a chambered follower, a pair of triangular wedge-blocks slidably engaging the transverse vertical face of the follower, their exposed faces being of unequal length, the blocks having angular bosses on their ends and the follower having central T-shaped guide channels in its horizontal walls, the stem of the T extending inwardly from the margin of the wall and its cross member being adjacent the vertical wall of the follower, the distance from either of the wedge faces of the block to the most remote point of the boss being greater than the width of the lateral extension of the channel.

7. A draft gear comprising, in combination, a chambered follower, a pair of triangular wedge-blocks slidably engaging the vertical face of the follower, the exposed sides of the blocks being of unequal length, the follower having one of its horizontal walls provided with a central guide channel extending inwardly from its margin and laterally at its inner end, and each of the blocks having an angular boss on one end for engaging the channel, the distance from either of the wedge faces of the block to the most remote point of the boss being greater than the width of the lateral extension of the channel.

In testimony whereof I affix my signature.
DONALD F. SPROUL.
